UNITED STATES PATENT OFFICE.

GEORGE CAPPS BEIDLER, OF NEWTON, KANSAS.

FOUNTAIN-PEN HOLDER.

1,107,644.

Specification of Letters Patent. Patented Aug. 18, 1914.

Application filed May 27, 1913. Serial No. 770,284.

To all whom it may concern:

Be it known that I, GEORGE CAPPS BEIDLER, a citizen of the United States, residing at Newton, in the county of Harvey and 5 State of Kansas, have invented certain new and useful Improvements in Fountain-Pen Holders, of which the following is a specification.

This invention relates to the subject of 10 safety holding devices for fountain pens, and has for its object the provision of a simple and practical device of this character having means for securely retaining a fountain pen in a pocket or other position, and 15 thereby guarding against accidental loss or dropping of the pen.

In addition to its general object of providing means for safely carrying and holding a fountain pen, the present invention 20 has in view a device that is so constructed as to constitute a complete case or holder for the pen so that it will be held in such a manner as to make it impossible for the cap part of the pen to be separated from the body 25 part of the pen in the handling thereof, thereby distinguishing from that class of fountain pen clips and holders which are attached directly to the fountain pen cap and thereby do not prevent the accidental 30 separation of the cap from the body of the pen, and consequently the dropping of the pen at times on that account.

With these and such other objects in view 35 that are necessarily incident to a device of the above character, the present invention consists in the novel construction, combination, and arrangement of parts hereinafter more fully described, illustrated, and claimed.

40 A preferable embodiment of the invention is shown in the accompanying drawings, in which—

Figure 1 is a perspective view of a fountain pen holder constructed in accordance 45 with the present invention. Fig. 2 is a longitudinal sectional view thereof showing by full and dotted lines respectively the manner in which the complete pen is retained within the holder and the manner in which it is

removed therefrom. Fig. 3 is a detail view 50 illustrating the manner of clipping or securing the holder within a pocket.

Like reference characters designate corresponding parts in the several figures of 55 the drawings.

The device as an entirety may be referred to as a holding bracket consisting of a main supporting strip designated by the numeral 1, a stationary cap piece 2 at one extremity of the strip and a socket member 3 at the 60 opposite end of the strip. The said strip 1 preferably consists of a single piece of sheet metal concave or convex in cross section to conform to the curvature of the fountain pen, and of a length somewhat greater than 65 the normal length of the conventional fountain pen. The said cap piece 2 is rigidly united to one end of the strip 1 and is of a dished form to constitute a receiving socket for the cap portion of the fountain pen, 70 while the opposite end of the fountain pen is adapted to be received within the inner open end portion of the socket member 3 and to bear against a follower plate 4 loosely arranged within the socket member 75 3 and normally held under spring pressure or tension by a presser spring 5 interposed between the said plate 4 and the bottom of the socket member 3.

When inserting a pen in place, one end 80 thereof is inserted into the socket member 3 and pressed against the plate 4 sufficiently to bring the opposite end of the fountain pen into the plane of the cap piece 2 so that by releasing the hold on the fountain pen 85 the spring 5 and plate 4 will move it into the retained position shown in Fig. 2. To release the fountain pen, it is simply necessary to move the same longitudinally against the presser spring 5 so as to release the same 90 from engagement with the cap piece 2. The supporting strip 1 has fitted thereto a fastening clip 6 preferably of the spring type and adapted to be engaged with the edge of a pocket or other receptacle as shown in 95 Fig. 3 of the drawings, or attached in any convenient position on or about any part of a garment.

What I claim is:

A fountain pen-holder comprising a supporting strip having at its upper end a fixed dished cap piece, and at its lower end a fixed 5 cylindrical socket member, a spring pressed follower plate confined within said socket and adapted to force a pen into holding engagement with the dished cap piece, and a

garment attaching device carried by said strip.

In testimony whereof I affix my signature ¹⁰ in presence of two witnesses.

GEORGE CAPPS BEIDLER.
